SHIRT

William J. Buford, Houston, Tex.

Application November 26, 1949, Serial No. 6,273

Term of patent 14 years

(Cl. D3—25)

To all whom it may concern:

Be it known that I, William J. Buford, a citizen of the United States of America, residing at Houston, Harris county, State of Texas, have invented a new, original, and ornamental Design for a Shirt, of which the following is a specification, reference being made to the accompanying drawing, forming a part thereof.

The single figure of the drawing is a front perspective view of a shirt, the important feature of this design residing in the collar portion and strips shown in full lines, the back part of the shirt being conventional.

I claim:

The ornamental design for a shirt, substantially as shown and described.

WILLIAM J. BUFORD.
